Patented Oct. 8, 1918.

FIG 1

FIG 2

FIG 3

Inventor
Albert Fugère.

By
William C. Linton
Attorney.

UNITED STATES PATENT OFFICE.

ALBERT FUGÈRE, OF MONTREAL, QUEBEC, CANADA.

MOISTURE-ABSORBER FOR TOBACCO-PIPES.

1,280,703.

Specification of Letters Patent.

Patented Oct. 8, 1918.

Application filed October 29, 1917. Serial No. 199,055.

To all whom it may concern:

Be it known that I, ALBERT FUGÈRE, a citizen of the United States; residing at Montreal, Province of Quebec, Canada, have invented certain new and useful Improvements in Moisture-Absorbers for Tobacco-Pipes; and I do hereby declare that the following is a full, clear, and exact description of the invention, such as will enable others skilled in the art to which it appertains to make and use the same.

The present invention relates to tobacco pipes and more particularly to an absorber adapted to be placed within the bowl of the tobacco pipe for absorbing the nicotine or any other moisture that may accumulate within the pipe.

An object of the present invention is to provide a removable absorber of the character aforesaid which may be easily and readily placed within the bowl of any tobacco pipe and readily adapted to be removed so that it may be cleaned.

With the above and other objects in view which will hereinafter appear as the description continues, the invention consists of the novel features of construction, combination and formation of parts as will be hereinafter more fully described and particularly pointed out in the appended claims.

In the accompanying drawings has been shown the simple and preferred form of the invention, it being, however, understood that no limitation is necessarily made to the precise structural details herein exhibited, but the right is hereby reserved to any changes, alterations or modifications to which recourse may be had that come within the scope of the claim without departing from the spirit of the invention or sacrificing the efficiency of the same.

In the accompanying drawings:

Figure 1 represents an ordinary smoking pipe partly in section having the moisture absorber embodying the present invention applied therein;

Fig. 2 is a bottom plan view of the moisture absorber forming the preferred form of the invention; and

Fig. 3 is a plan view of a blank embodying the preferred form of the invention.

Referring now more particularly to the accompanying drawings wherein like and

corresponding parts are designated by similar reference characters throughout the several views,

The tobacco pipe as herein shown is of ordinary and well known construction having a bowl 1 in which is to be placed the moisture absorber. This absorber as shown in Figs. 1 to 3 inclusive of the drawings is stamped from a single sheet of material forming a disk or body portion 2 having extending diametrically opposite therefrom the arms 3. Also extending from the periphery of the body portion 2 at right angles to the arms 3 is a shorter arm 4 carrying a disk 5 of less diameter than the disk 2 and the disks 2 and 5 are each provided with a plurality of perforations. In bending the blank holder in proper shape the arms 3 are bent upwardly having their extremities 6 bent outwardly to form a pair of resilient supporting arms whereas the shorter arm 4 is bent downwardly and the disk 5 adapted to rest below the disk 2 in spaced relation therefrom and this disk 5 is given a concave configuration. A suitable absorbent material 7 is adapted to be retained between the disks 2 and 5 so that any spittle or other moisture coming in contact with the absorbing material will be readily absorbed and prevented from traveling through the stem of the pipe into the mouth of the smoker. The holder carrying the absorbent material is adapted to be placed within the bowl of the pipe as shown in Fig. 1 and then the tobacco placed upon the holder. In this manner the tobacco, ashes or other moisture from the tobacco will be retained by means of the holder and absorbent material and prevented from traveling through the stem of the pipe, thereby giving the smoker a substantially dry smoke.

In cleaning the pipe the operator may grip the arms 3 thereby removing the holder and absorber from the bowl of the pipe and at the same time carrying any remaining tobacco or ashes contained within the bowl of the pipe, thereby perfectly cleaning the same. When the absorber has been removed from the bowl of the pipe new absorbent material may be placed within the holder should the absorbent material contained therein be full of moisture.

Having thus fully described my inven-

tion, what I claim as new and desire to secure by Letters Patent is:

A moisture absorber for tobacco pipes stamped from a single sheet of metal comprising an enlarged disk body portion having perforations therein, a pair of resilient arms extending diametrically opposite from the edge of said body portion, a shorter arm formed with the edge of said body portion and extending at right angles to said resilient arms, a perforated disk formed in-

tegral with the outer end of said shorter arm and being of less diameter than the disk body portion, said shorter arm adapted to retain the disk of less diameter below 15 said disk body portion and in spaced relation therewith and said disks adapted to retain absorbent material therebetween substantially as and for the purpose specified.

In witness whereof I have hereunto set 20 my hand.

ALBERT FUGÈRE.
